United States Patent Office

Des. 229,603

Patented Dec. 18, 1973

229,603

CAN OPENER

Alan F. Eckel, Chicago, Ill., assignor to Sears,
Roebuck and Co., Chicago, Ill.

Filed Apr. 6, 1972, Ser. No. 241,894

Term of patent 14 years

Int. Cl. D7—99

U.S. Cl. D8—36

FIG. 1.

FIG. 2.

FIG. 3.

FIG. 4.

FIG. 5.

FIG. 6.

FIG. 1 is a front perspective view of a can opener showing my new design;

FIG. 2 is a front elevational view thereof;

FIG. 3 is a side elevational view thereof;

FIG. 4 is a side elevational view thereof, showing the side opposite to that shown in FIG. 3;

FIG. 5 is a rear elevational view thereof; and

FIG. 6 is a top plan view thereof.

The conventional power cord is fragmentarily shown in FIGS. 3, 4 and 6.

I claim:

The ornamental design for a can opener, as shown and described.
